VIBRATOR

William W. Garstang, Indianapolis, Ind.

Application February 25, 1935, Serial No. 8,065

8 Claims. (Cl. 200—90)

My invention relates to improvement in vibrators and particularly that type of vibrator used in power units for supplying necessary power current to radios and devices of this character.

5 One of the objects of my invention is to provide a vibrator electromagnetically operated in which the various parts of the vibrator are so constructed that they may be readily and accurately assembled.

10 In certain types of vibrators the structure comprises a vibrating reed having disposed on opposite sides thereof disk-like contacts, which disk-like contacts are adapted during the vibration of the reed to engage similarly constructed 15 disk-like contacts mounted on resilient fingers. It is quite essential, from the standpoint of long life and accurate operativeness, that these contacts be correctly and accurately aligned so that the entire surface of such contacts will engage 20 during the vibration of the reed with the entire surface of the remaining contacts, and it is one of the objects of my invention to provide a structure wherein this alignment may be obtained with a minimum of assembly cost.

25 Other objects and advantages of my invention will appear more fully hereinafter in the appended specifications and claims.

For the purpose of disclosing my invention I have illustrated certain embodiments in the accompanying drawing in which

Fig. 1 is a side elevation of an electromagnet embodying my invention;

Fig. 2 is a front elevation thereof;

Fig. 3 is a disassembled perspective view of the reed and contact finger supporting means; Fig. 4 is a sectional view of another embodiment of my invention mounted on a supporting plug in the housing;

Fig. 5 is a bottom plan view of the structure 40 illustrated in Fig. 4;

Fig. 6 is a sectional view taken on the line 6—6 of Fig. 4, and

Fig. 7 is a diagrammatic view of a circuit arrangement for one application of my invention.

45 In the structures illustrated, referring more particularly to the structures illustrated in Figs. 1 to 3, I provide an elongated base which may be formed of cast iron to provide a vertical member 1 and a horizontally-disposed member 2, extending at right angles to the vertical member 1 and adapted to carry the electromagnet. It will be understood that the reference to a vertical member 1 and a horizontal member 2 on the 50 base is purely arbitrary and these expressions

are used primarily for the purpose of description.

The electromagnet consists in a suitable winding 3 surrounding a core 4 forming at its free end a pole piece 5 and this core 4 is connected to the arm 2 of the base. The vibrating reed 6 and its associated contact-carrying reeds 7 and 8 are mounted at the opposite end of the vertical member 1 of the base and this vibrating reed 6 carries at its free end an armature 9 and a pair of contact points 10 and 11 which are preferably formed of suitable contacting material in the form of metal discs preferably riveted to the opposite sides of the reed. Each of the spring fingers 7 and 8 is correspondingly provided at its free ends with contacts 12 and 13 preferably of the same material as the contact discs 10 and 11, and are adapted to align with these contacts although with the reed 6 in its normal or untensioned position no engagement of the contacts is made.

The vibrating reed 6 at its base is provided with a squared opening 14 and each of the spring fingers 7 and 8 has at its base an enlarged squared portion 15 provided with a squared opening 16. Likewise, the vibrating reed 6 and the spring fingers 7 and 8 at their bases are provided with integrally-extending teats 17 to which suitable conductor wires may be attached.

The base portion 1 at its lower end is provided with a raised boss 18 in which is formed a squared socket 18' surrounding the opening extending clear through the base for the assembly screw 19. The assembly screw provides the mounting for the vibrating arm or finger 6 as well as a mounting for the spring fingers 7 and 8 and in order that these parts should be properly insulated from one another the mounting screw 19 is surrounded by a bushing 20 and to insure the proper alignment of the fingers and reed this bushing is made square so that its lower end will socket into the squared recess 18' and so that the bushing will enter the squared openings 14 and 16 in the reed and fingers. Due to the fact that this squared opening 18' is properly aligned relatively to the face of the pole piece 5, the bushing being squared and locked against possible rotation by its squared socket 18', will properly align the top edge of the vibrating reed 6 and its associated armature 9 with the face of the pole piece 5 and will also properly align the spring fingers 7 and 8 respectively to the reed 6 to insure the proper alignment of the contact points on these respective members.

In assembly, in the specific structure illustrated, I provide adjacent the base, first an insulating washer 21; then a steel or metal washer 22; then the vibrating reed 7. On top of this reed 5 I place a steel spacer washer 23 and an insulating washer 24. Next is arranged a steel washer 25, or, as a matter of fact, two steel washers 25 between which is mounted the vibrating reed 6 and in contact with the vibrating reed is a 10 conductor plate 26 having a tail 27. Next is placed an insulating washer 28, a steel washer 29, and between the steel washer 29 and a second steel washer 30 is arranged the spring finger 8. On top of this steel washer is mounted an insulating washer 31, and on top of this is a clamping washer 32 between which and the nut 33 is adapted to be clamped the tail piece 27. These 15 various washers, both metal and insulated are preferably square and all are provided with square openings adapted to receive the squared bushing 20. By the above-described mounting it is apparent that the vibrating reed and associated spring fingers are all perfectly insulated from one another by the bushings and insulating washers so that there is no danger of electrical contact between these members. It is desirable in the particular structure illustrated that the vibrating reed should be grounded on the frame or base and to this end the conductor 20 washer with the tail piece 27 is provided, the tail piece being brought out and secured beneath the nut 33 which, it will be seen through the screw, is in contact with the frame or base portion 1. Suitable leads are taken off from the 25 different teats 17 on the different members for connection to the suitable conductors through which the current is adapted to pass, and in order that these leads may be more or less rigidly held relative to the teats, these leads are brought in 30 through holes formed in the base member 1. It is quite apparent from this assembly that the squared bushing locked in its position in its squared socket maintains the spring fingers as well as the vibrating reed in absolute and correct 35 alignment to maintain the contacts in correct aligned position and that this alignment is obtained more or less automatically in the assembly operation.

As before stated, the base is formed of cast 50 iron to give a large mass of iron in the magnetic circuit of the electromagnet, and the squared socket for the bushing 20 is cast in the base at the time of its formation.

In Figs. 4, 5 and 6 I have shown an electromagnet of the same substantial construction as that illustrated in Figs. 1 and 2 with the exception that in this structure, in order to increase the mass of iron, I have provided at each end a pair of horizontal arms 2 and 2a and these arms 55 instead of being substantially square or rectangular as in the structure illustrated in Figs. 1 and 2, preferably take somewhat the form of discs. This structure is mounted on a metallic base 34 provided with plug-in prongs 35 extending through openings in the base and secured to an insulating disc 36 mounted in the base. This base is provided with an annular flange 37 60 adapted to receive a tubular casing 38 and interposed between the bottom of the base and the 65 vibrator is suitable sound-deadening material 39 which may be of sponge rubber or felt or other desired material. Likewise, the casing or tube 38 is lined with sound-deadening material 39' and similar sound-deadening material 40 is 70 interposed between the top of the casing and

the top of the vibrator. This provides a structure which may be plugged in a suitable receptacle and by which any vibrations set up during the operation of the vibrator are absorbed to prevent noise or interference where the device is 5 used in radio construction.

In Fig. 7 I have illustrated one application of my vibrator for converting direct to alternating current. In this figure I have illustrated a transformer wherein the secondary 41 constitutes the 10 power output. The primary 42 is connected intermediate of its ends with a power supply 43. The opposite ends of the primary are connected respectively to the fingers 7 and 8. The electromagnetic winding has one side connected to the power 15 supply 43 and the opposite side connected to the finger 7, while the vibrating reed 6 is connected to one side of the power supply 43. Under these circumstances when circuit is closed through the electromagnetic winding the reed will be attracted 20 in a direction to close the circuit through one portion of the primary winding 42 and at the same time close a short circuit through the electromagnetic winding. This will, of course, immediately release the armature edge of the vibrating 25 reed, permitting the reed, which has been stressed, to vibrate in the opposite direction, closing the circuit through the opposite side of the primary winding in a reverse direction.

I claim as my invention:

1. In a circuit-controlling device, the combination with a base having an extension at one end projecting at substantially right angles thereto, of an electromagnet supported on said extension and having a core extending parallel with the base 35 and provided with a pole face substantially at right angles to the base, of a mounting post extending from said base, an irregularly shaped socket formed in said base and surrounding said post and having at least one wall definitely positioned relatively to said core face, an irregularly shaped bushing surrounding said post and shaped at one end to conform to the seat in said socket, a plurality of contact carrying members mounted on said post and having irregularly shaped openings to receive said bushing and an armature having a portion arranged parallel with and in close proximity to said core face and carried by one of said contact carrying members.

2. In a circuit-controlling device, the combination with a base having an extension at one end extending at right angles to said base, of an electromagnet mounted on said extension having a core extending parallel with the base and provided with a pole face substantially at right angles to 55 said base, a mounting post extending from said base, an irregularly shaped socket formed in said base and surrounding said post and having one wall thereof parallel to the core face of said magnet, an irregularly shaped bushing surrounding 60 said post and having a bottom portion shaped to conform to and seat in said socket, a plurality of contact carrying members mounted on said post having irregularly shaped openings to receive said bushing, one of said contact carrying members 65 having an armature on its end, terminating adjacent to and parallel with said core face, and means for securing said contact carrying members on said post.

3. In a circuit-controlling device, the combination with a base having a right angle extension at one end, of an electromagnet mounted on said extension and having a core extending parallel with the base and provided with a core face substantially at right angles to said base, a mounting 75

post extending from said base substantially at right angles thereto, a rectangularly shaped socket formed in said base and surrounding said post and having one wall parallel with said core face, a rectangularly shaped bushing surrounding said post and having one end seated in said socket, a plurality of contact carrying members mounted on said post and parallel with the base and having rectangular shaped openings to receive said bushings, 10 and an armature carried by one of said contact carrying members having an edge portion arranged parallel with and in close proximity to said core face.

4. In a circuit-controlling device, the combination with a base having an extension at one end projecting at right angles to said base, an electromagnet supported on said extension having a core extending parallel with said base and having a core face extending at right angles to said base, 15 a mounting post bolt extending through an opening in said base, said opening on one face of the base being countersunk to receive the head of said bolt, the opposite face of said base having a raised portion provided with an irregularly shaped socket 20 surrounding said post opening and having one wall definitely positioned relatively to said core face, a bushing surrounding said post having an irregularly shaped end conforming to and seated in said socket, a plurality of contact carrying members mounted on said post and having irregularly shaped openings therein to receive said bushing, an armature mounted on one of said contact carrying members and having a portion arranged parallel with and in close proximity to 25 said core face.

5. In a circuit-controlling device, the combination with a base having an extension projecting at right angles to said base at one end thereof and having an opening extending through 30 said base, said opening being countersunk on one face, of an electromagnet mounted on said base having a core extending parallel with the base provided with a core face substantially at right angles to said base, a bolt extending through 35 said opening and having its head fitting in said countersunk opening, the opposite face of said base having a raised portion, having a squared recess formed therein and surrounding said opening and having a wall thereof definitely related 40 to said core face, a square bushing surrounding said post and seating in said recess, a plurality of contact carrying fingers having squared openings receiving said bushing, and an armature carried by one of said contact carrying members, 45 and having a portion thereof arranged parallel with and in close proximity to said core face.

6. In a circuit-controlling device, the combination with a base having an extension at one

end projecting at right angles to said base, of an electromagnet mounted on said extension having a core extending parallel with the base and provided with a core face extending at substantially right angles to said base, a mounting 5 post extending from said base, an irregularly shaped socket on said base surrounding said post and having its walls in fixed relation to said pole face, an irregularly shaped bushing surrounding said post and shaped at one end to 10 conform to and seat in said socket, a plurality of contact carrying members mounted on said post and having irregularly shaped openings to receive said bushing, and an armature having a portion arranged parallel with and in close proximity to 15 said core face and carried by one of said contact carrying members.

7. In a circuit-controlling device, the combination with a base having an end portion extending at right angles to the base, an electromagnet mounted on said end portion and having a core extending parallel with the base provided with a pole face substantially at right angles to said base, a contact-carrying post at the opposite end of said base extending parallel 25 with said first-mentioned end portion, said base having an irregularly-shaped socket formed in the face thereof and surrounding said post, a vibrating reed and a pair of contact-carrying fingers arranged on opposite sides of said reed 30 and mounted on said post, said reed and fingers having irregularly-faced openings to receive said bushing, said reed having an armature on the free end thereof terminating adjacent to and parallel with a pole face of said electromagnet, 35 and contact members mounted on said fingers and on opposite sides of said reed.

8. In a circuit-controlling device, the combination with a base having a pair of extensions at its opposite ends projecting at right angles to 40 said base, an electromagnet mounted on one of said extensions and having a core extending parallel with said base having a pole face substantially at right angles to said base, a supporting post extending from said base parallel with said 45 extensions, an irregularly-shaped socket formed in one face of said base, an irregularly-shaped bushing surrounding said post and having its lower end shaped to conform to and seat in said socket, a vibrating reed and a pair of contact-carrying fingers arranged on opposite sides of 50 said reed mounted on said post and having irregularly-shaped openings to receive said bushing, and an armature on the end of said reed terminating adjacent to and parallel with the 55 pole face of said electromagnet.

WILLIAM W. GARSTANG.
